UNITED STATES PATENT OFFICE.

EDWARD C. FAIN, OF WETUMPKA, ALABAMA.

COIN-CONTROLLED MECHANISM FOR VENDING-MACHINES.

1,240,187.

Specification of Letters Patent. Patented Sept. 18, 1917.

Application filed October 21, 1916. Serial No. 126,940.

To all whom it may concern:

Be it known that I, EDWARD C. FAIN, a citizen of the United States, residing at Wetumpka, in the county of Elmore and State of Alabama, have invented certain new and useful Improvements in Coin-Controlled Mechanisms for Vending-Machines; and I do hereby declare the following to be a full, clear, and exact description of the invention, such as will enable others skilled in the art to which it appertains to make and use the same.

The invention relates to coin controlled mechanism for vending machines.

The object of the present invention is to improve the construction of coin controlled mechanism for vending machines and to provide a simple, practical and efficient device designed particularly for vending bottles and analogous receptacles but capable of general application and of being operable only when a proper coin or a check of the proper size is deposited in the machine.

With these and other objects in view, the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawings

Figure 1 is a front elevation of coin controlled mechanism constructed in accordance with this invention,

Fig. 2 is a side elevation of the same partly in section,

Fig. 3 is a detail sectional view on the line 3—3 of Fig. 2,

Fig. 4 is a detail sectional view on the line 4—4 of Fig. 1,

Fig. 5 is a detail sectional view on the line 5—5 of Fig. 2.

Fig. 6 is a detail sectional view illustrating the construction of the coin chute closure.

Like numerals of reference designate corresponding parts in the several figures of the drawings.

In the accompanying drawings in which is illustrated the preferred embodiment of the invention, the numeral 1 indicates a substantially semi-cylindrical rotary valve or

cut-off provided at its ends with circular heads 2 and 3 having outwardly projecting longitudinally disposed journals 4 mounted in suitable bearings of a standard 5 and an arm 6 of a bearing bracket 7. The rotary valve or cut-off is arranged to operate in conjunction with an inclined bottle chute 8 designed to be constructed similar to that illustrated in my co-pending application 65 executed of even date herewith for an improvement in bottle vending machines. The head 3 is provided with a segmental series of spur teeth 9 arranged to mesh with a pinion 10 mounted on a suitable stub shaft 70 or pivot 11 and rotated in opposite directions by the means hereinafter described to first rotate the cut-off or valve in one direction and then in the opposite direction to carry the said cut-off or valve from its 75 closed to its open position and vice versa for successively feeding bottles. The pinion 10 meshes with lower teeth 12 of a slidable rack bar 13 provided also with upper teeth 14. The slidable rack bar which is also provided with upper and lower longitudinal flanges 15 to slide in a way 16 of the standard 5 has its lower rack continually in mesh with the pinion 10 and its upper rack formed by the teeth 14 is normally spaced from a 80 toothed quadrant or gear 17 secured by a set screw or other suitable means to a horizontal shaft 18 and being a part of a gear proportioned two to one to the pinion so that a quarter revolution of the quadrant 85 17 will rotate the pinion 10 and the cut-off or valve one-half a revolution, the toothed head 3 of the valve being the same diameter as the pinion 10. The upper rack 14 is shorter than the lower rack 12 and the shaft 95 18 and an operating lever may be freely oscillated without communicating any movement to the rack bar when there is no coin deposited in the mechanism.

The coin for operating the mechanism or for enabling the mechanism to be operated by the lever is deposited in a coin chute consisting of a fixed inclined upper section 20 provided intermediate of its ends with a quarter bend 21 and having its lower end located above an upper tapered or funnel shaped portion 22 of a vertically disposed movable section 23 of the coin chute or tube. The movable section 23 is mounted on a link 24 pivoted at its upper end at 25 to a bracket 100 26 and having its lower ends pivoted at 26^a to the inner or rear end of the link 27. 105 110

The link 27 is pivoted by a pin 28 to the toothed quadrant at one end of the series of teeth of the toothed quadrant. By this construction the movable section will swing 5 with the quadrant and the operating lever when the latter is oscillated.

The upper rack of the rack bar is normally maintained out of engagement with the teeth of the toothed quadrant by a 10 coiled spring 27^a connected at one end to the rack bar and at the other end to the casing 28^a and adapted also to return the cut-off or valve to its initial position after an operation of the machine in which the 15 coin controlled mechanism is installed. The operating mechanism is also returned to its initial position by a coiled spring 29 secured at one end to the casing and at the other end to the pin which pivots the link 20 27 to the quadrant. By this construction the parts will always be in proper position for an operation of the machine. The rack bar is provided at its inner or rear end with a notch or recess 30 having an inclined 25 bottom 31 and adapted to support a coin 32 partially within the lower end of the movable section 23 of the coin chute as clearly illustrated in Fig. 3 of the drawings. This will enable the operating mechanism to actuate the rack bar sufficiently to carry the latter into position for engaging or meshing with the toothed quadrant and when the quadrant meshes with the upper rack of the 30 slidable rack bar a continued movement 35 of the parts will serve to free the coin and permit the same to roll down the inclined bottom of the notch or recess. By this construction only a coin or check of the proper size will produce an operation of the machine and if desired the coin controlled mechanism may be equipped with any desired form of coin detector so that only a coin of the proper denomination will permit an operation of the machine.

45 When a coin is deposited in the machine it will roll down the inclined coin chute and be deposited in the flaring or funnel shaped upper portion of the vertical coin tube or chute and will slide down the latter until 50 it reaches the rack bar which will support the coin in engagement with the movable chute and connect the rack bar with the operating mechanism. This will permit the rack bar to be engaged by the quadrant and 55 a full stroke of the operating lever or handle 19 will rotate the pinion and the cut-off or valve one-half of a revolution and cause the discharge of a bottle or other object. After the machine has been operated 60 through the forward or outward movement of the handle, the parts will be returned to their initial position by the coiled spring and it will be impossible to secure a second operation of the machine until a second coin 65 is deposited in the same. The horizontal

shaft which may be of any desired length can be connected with any number of sets of coin controlled devices so that one or more of such coin controlled devices may be operated at each operation of the horizontal shaft. By this construction, a plurality of coin controlled devices may be operated either independently or simultaneously.

The rack bar is limited in its forward 75 movement by a projection or pin 33 which is arranged to engage the standard 5 as clearly illustrated in Fig. 5 of the drawings.

The slot or inlet of each of the coin tubes 30 or chutes is automatically closed by a vertical slidable plate or closure 34 carried by a suitable rod 35 and movable upwardly and downwardly through a recess or slot 36 to open and close the coin chute. The 35 rod operates in suitable guides 37 and it is connected at its lower end to a lever 38 pivoted at an intermediate point at 39 and having a depressible plate or portion 40 located in the path of and adapted to be 45 maintained in a depressed condition by the bottle adjacent to the cut-off or valve and when the last bottle has been discharged from the apparatus the lever is automatically movable to cause the plate or closure 50 to cover the coin slot and prevent a coin from being introduced into the vending machine.

What is claimed is:—

1. Coin controlled mechanism including 100 an oscillatory gear, a movable coin chute connected with the gear, a rack bar having its teeth normally out of mesh with the oscillatory gear, and provided with means adapted to be engaged by a coin for connecting the rack bar with the movable coin chute to cause a movement of the rack bar to carry its teeth into mesh with the oscillatory gear, the continued movement of the rack bar and the chute operating to dislodge 110 the coin.

2. Coin controlled mechanism including 115 an oscillatory gear, operating mechanism connected with the gear for actuating the same, a pivotally mounted coin chute connected with the gear, a slidable rack bar having its teeth normally out of mesh with the oscillatory gear, said rack bar extending beneath the coin chute when the latter is in its initial position and adapted to support 120 a coin for connecting the rack bar with the chute to cause a preliminary movement of the rack bar to carry its teeth into mesh with the teeth of the oscillatory gear.

3. Coin controlled mechanism including 125 an oscillatory gear, a pivoted coin chute mounted to swing on a horizontal axis, a link connecting the coin chute with the gear to cause the former to swing in union with the latter, a slidable rack bar having its 130

- teeth normally spaced from and arranged out of mesh with the teeth of the gear, said rack bar extending beneath and having coin receiving means adapted to support a coin 5 in the lower end of the coin chute to cause a preliminary movement of the rack bar by the operating means to carry the teeth of the rack bar into mesh with the teeth of the said gear.
- 10 4. Coin controlled mechanism including an oscillatory gear a rack bar located beneath and having its teeth normally arranged out of mesh with the rack bar, a pivotally mounted coin chute connected with the gear to swing in unison with the latter and arranged above the rack bar, the rack bar being provided with a coin receiving notch having a laterally inclined bottom and adapted to support a coin for connecting the 15 rack bar with the operating means.
- 15 5. Coin controlled mechanism including a quadrant, a slidable rack bar located beneath the quadrant and having upper and lower racks, the upper rack being normally out 20 of engagement with the quadrant, a movable coin chute connected with the quadrant and located above the rack bar for depositing a coin thereon for connecting the rack bar with the quadrant to carry the upper teeth 25 of the rack bar into mesh with the said quadrant, a valve or cut-off, and gearing for connecting the valve or cut-off with the lower teeth of the rack bar.
- 20 6. Coin controlled mechanism including a
- coin chute having a fixed inclined section 35 and a substantially vertical section provided with an enlarged tapered portion located beneath the lower end of the inclined section, said vertical section being movable, an oscillatory gear connected with the movable section of the coin chute, a rack bar located beneath the oscillatory gear, and having teeth normally arranged out of mesh with the said gear, said rack bar extending beneath the vertical coin chute section and provided with means for engaging a coin to support the same said coin operating to connect the rack bar with the coin chute and a valve or cut-off actuated by the rack bar.
- 25 7. Coin controlled mechanism including an oscillatory gear, a movable coin chute connected with and actuated by the gear, a rack bar located beneath the gear and having teeth normally arranged out of mesh with the said gear, and movable into position 40 for meshing with the gear, said rack bar extending beneath the coin chute and provided with means for engaging the coin to connect the rack bar with the oscillatory gear and separate means for automatically 45 returning the oscillatory gear and the rack bar to their initial position.
- 30 In testimony whereof I affix my signature in presence of two witnesses.
